PORTABLE BROILER

Blair N. Winning and John F. Trotter,
Kansas City, Mo.

Application February 13, 1950, Serial No. 143,938

1 Claim. (Cl. 126—25)

2

Fig. 5 is a perspective view of a spit for use in the grill box of the stove.

Fig. 6 is a perspective view of a modification of the invention wherein an oven replaces the hood of the modification shown in Fig. 1, with a corner portion of the grill box cut away to reveal assembly features at that point.

Fig. 7 is a vertical cross section taken along the lines 7—7 of Fig. 6 in the direction of the arrows.

10 Fig. 8 is a horizontal cross section taken along the lines 8—8 of Fig. 7 in the direction of the arrows.

Referring more particularly to the drawings, in the embodiment of our invention shown in 15 Fig. 1 the reference numeral 9 denotes a wheeled carriage having vertically extended legs 10, in the upper ends of which are formed sockets 11. Joining the legs at the sockets and near the bottom are pairs of parallel angle bars 12 and 12a respectively, and disposed in the top of the framework thus formed is a receptacle or ash tray 13 having its out-turned upper edges resting upon the horizontal surface of the bars 12.

20 A looped hand bar 14, demountably attached by means of the wing nuts 11a to the sockets at 25 one end of the frame, as indicated, and a single pair of wheels 15, attached to the lower ends of the legs at the opposite end of the unit, provide a means for moving the carriage from place to place as desired.

25 In the sockets 11 reside grill support bars 16 in the upper ends of which are located pins 16a. Resting upon the upper ends of these bars, with holes therein in register with the pins 16a, are the out-turned upper edges of an open-end, 30 open-top trough forming a firebox 17 having its downwardly converging side walls and floor perforated by a plurality of draft holes 17a. The open ends of the firebox are closed by displace- 35 able wedge-shaped baffles 18, indicated in Fig. 3, which may be moved inwardly along the floor of the box to change the size of the fuel bed or to concentrate the source of heat at any desired point. A convenient utility shelf 19 is located on 40 the outside of the wheeled end of the carriage, being joined to the lower ends of the supporting rods 16 below the end of the firebox as indicated.

45 Resting upon the upper edges of the firebox, with its in-turned lower edges having holes in 50 register with the pins 16a of the bars 16, is an open top grill box having vertical side and end walls 20 and 21, respectively. Located in each of the end walls 21 are three laterally spaced, vertically elongated slots 22 having in one side 55 thereof longitudinally spaced, downwardly in-

1 This invention relates to stoves and refers more particularly to a portable stove suitable for indoor and outdoor broiling, barbecuing and similar cooking operations.

The principal object of our invention is to provide for sportsmen, campers, or for use in outdoor cooking or indoor cooking over a hearth, a portable stove unit suitable for broiling, barbecuing, smoking, baking and similar purposes, which possesses the desirable advantage of simplicity of operation combined with well regulated heat control. To this end an important feature of our invention resides in the provision in a portable stove of selective levels over the heating unit to which the food may be easily moved during the cooking process. In this connection it is an additional feature of the invention that the heating unit comprise a fire box or trough having displaceable ends whereby the fuel bed may be concentrated, dispersed or changed in size as desired.

Another object of our invention is to provide for the purpose described a portable knock-down stove which may be easily moved in either the assembled or disassembled condition and used as an integral, self-sustaining unit, or separately, in connection with an interchangeable hood or oven. Therefore, a salient feature of the invention resides in the assembly of the stove as a combination of demountable, separate heating and cooking units on a wheeled carriage.

An additional object of our invention is to provide in a portable stove of the character described a unit which is highly versatile, economical to produce, attractive in appearance and easily packed for storage.

Other and further objects of our invention, together with the features of novelty, will appear in the course of the following description.

In the accompanying drawings, which form a part of the instant specification and are to be read in conjunction therewith, and in which like reference numerals are employed to identify like parts of the various views:

Fig. 1 is a perspective view of a portable stove suitable for barbecuing, broiling and similar purposes, with a fragmentary portion of the frame cut away to reveal the socket assembly features,

Fig. 2 is a horizontal cross section taken along the lines 2—2 of Fig. 1 in the direction of the arrows,

Fig. 3 is a perspective view of a baffle designed for use in the fire box of the stove,

Fig. 4 is a vertical cross section taken along the lines 4—4 of Fig. 1 in the direction of the arrows,

clined notches 23, and over the notches of the center slot are located pins 23a whose function will be described in more detail presently. Easy access to the grill and fire boxes is provided by means of a hinged downwardly opening door 24 located in one of the side walls 20.

In connection with the grill box, there is provided with the stove a grill 25, or wire mesh or other suitable material, having supports 26 to which are attached removable handles 27. When the grill is placed in the grill box the supports 26 reside in the oppositely disposed notches 23 (of the outer slots 22), as indicated in Figs. 1 and 2, with the grill handles 27 affixed to the ends of the supports on the outside of the box as shown.

Referring to Fig. 5, there is also provided a spit 28 having one end sharpened, tines on the shank, and the other end forming an L-shaped crank. Adjacent the crank on the shank of the spit there is fixed a disk-shaped metal plate 29 perforated by diametrically opposed holes 29a which are aligned to register with the above mentioned pins 23a when the spit resides in the notches 23.

In operation the spit is placed in the grill box so that its ends reside in the notches of the center slots 22, as indicated in Fig. 1, in such manner that the pins 23a over the notches will engage the holes in the plate 29, preventing turning of the spit when the plate is flush against the end wall of the box.

As can best be appreciated from Fig. 4, the spit can be used alone or in conjunction with the grill, and both may be adjusted by means of the notches in various positions over the firebox, providing a greater or less intense cooking heat as desired. With this arrangement, however, it can be seen that an additional position, or fourth level of heat, is provided for the grill when it is used without the spit, since the grill supports may then be rested in any of the three available notches as well as dropped to the lower ends of the slots directly over the firebox.

For the purpose of retaining the heat and protecting the food being cooked, in the embodiment of our invention presented in Fig. 1 there rests upon the top of the grill box a demountable hood 30 having its lower edges grooved to receive the upper edges of the grill box. However, the stove is operable without the hood, and it is contemplated that a hot plate, additional grill box, or other auxiliary attachments may be employed with the unit.

In the modification of our invention shown in Figs. 6 and 7, there is provided in place of the hood a double-doored, open-bottom oven 31. The oven is demountably attached to the grill box by means of inset grooves along the bottom edges which are adapted to receive the upper edges of the grill box. The end walls 32, top 33, and side wall 34 opposite the oven doors are lined with asbestos or other suitable insulating material over which is fastened a thin metal inner lining 35. Centrally disposed in the top of the oven is a flue 36 with a damper 37 which, together with the manipulation of the firebox baffles, provides a further means of heat control. Secured to the top of the oven are a plurality of hooks 38 from which meat may be suspended for smoking, baking or roasting.

In connection with this modification of the invention, a water pan 39, resting upon a supporting frame 40 which has removable handles 41, similar to those of the grill, is placed in the grill box between the fire unit and the grill, in the manner indicated in Figs. 6, 7 and 8. Thus de-

cated, the water pan prevents direct contact of the cooking food with the radiant heat of the fire unit, deflects the smoke and heat around the grill into the oven, and enables baking with the resultant water vapor providing the proper humidity necessary to cause meats to retain their juices.

Whether the stove is being used for roasting, broiling, or baking, the desired heat for the operation may be attained in several ways. It is possible, by moving the baffles 18 toward the center of the firebox, to change the size of the heat source or to concentrate the heat at any desired point. Lowering or raising the spit or grill in the notches makes it possible to uniformly sear meat in an intense heat at a low level or to slowly simmer it with less heat at a higher level. Regulation of the damper in the flue of the oven provides further heat control for baking purposes.

At all times one has easy access to the cooking units. The handles of the grill and water pan extending on the outside of the grill box allow adjustment to the desired levels without interrupting the cooking process. By means of the crank the spit may be continuously turned, or it may be pushed inwardly so that the plate 29 is engaged by the pins 23a to hold the spit in any one of four cooking positions.

In addition to having these advantages, the stove has the further advantage of being portable and easily disassembled. It may be readily moved by one person by means of the hand bar on the wheeled frame. To disassemble the unit, one has but to lift the hood or oven from the top of the grill box, lift the grill box from its position over the firebox, remove the firebox from the upper ends of the support bars, and remove the displaceable ash tray and support bars from their sockets. The firebox, ash tray and supports can be easily stored in the grill box when it is desired to transport the stove as a compact unit. The wheeled frame and hood can be moved separately, but the stove can be used without the frame either indoors or outdoors, in connection with any other type of heating unit over which the grill box may be placed. For example, the grill box and hood or oven may be placed over an outdoor pit or hearth and used separately, or the grill box alone may be used in an indoor hearth or over the burner of a stove or similar heating unit.

Thus it can be seen that we have provided a stove for barbecuing, roasting or similar purposes which has the advantages of a portable unit having effective heat control, selective levels for cooking, and versatility in that it may be converted, by the use of the oven and water pan, to baking or other cooking operations.

From the foregoing it will be seen that our invention is well adapted to attain the ends and objects hereinbefore set forth together with other advantages which are obvious and which are inherent to the invention.

It will be understood that certain features and subcombinations are of utility and may be employed without reference to other features and subcombinations. This is contemplated by and is within the scope of the claim.

Inasmuch as many possible embodiments may be made of the invention without departing from the scope thereof, it is to be understood that all matter herein set forth or shown in the drawings is to be interpreted as illustrative and not in a limiting sense.

Having thus described our invention, we claim:

In a portable knock-down stove, the combina-

tion of a grill box open at the top and bottom, each opposite end of the grill box containing a pair of laterally spaced vertically elongated slots each having along one side a series of vertically spaced notches extending diagonally downward from the slot, a substantially horizontal grid between said walls with stems projecting outwardly through said slots and seatable in said notches to hold the grid at selectable levels within the grill box, a separable trough-shaped open-ended firebox under the grill box, and a pair of closure members for the open ends of said trough-shaped firebox, said members resting on the trough and movable axially thereof to adjust the size and position of the space in the firebox between the closure members, each of the closure members having a vertical outside face and a sloping inside face both disposed crosswise of the trough and conforming in contour with the cross-sectional contour of the trough, said inside faces confronting one another and forming downwardly converging end walls for the firebox.
